POLAR QUINONYL SULPHONAMIDES AS
PRINTING AIDS

Roy Herman Kienle and Chester Albert Amick,
Bound Brook, N. J., assignors to American Cy-
anamid Company, New York, N. Y., a corpora-
tion of Maine

No Drawing. Application July 1, 1943,
Serial No. 493,131

10 Claims. (Cl. 8—76)

This invention relates to a new type of dyeing and printing assistant, dye compositions containing these assistants and products printed therefrom.

Use of printing-color pastes containing dyes, particularly in printing operations using vat dyes, is sufficiently well-known so that the procedure has become almost standardized. The actual color source may be either a dye paste or a dye powder. In addition to the real color, a dye paste usually contains agents to prevent drying-out, settling and/or freezing. Dye powders, not being subject to these difficulties, do not require these agents but they usually contain agents or are so processed as to promote dispersibility.

In either case, the dye paste or dye powder must be admixed with suitable thickener, usually a gum dispersion, to form a printing-color paste which is suitable for application. In the case of vat dyes, it is also necessary to add a reducing agent and usually an alkali. Because the color yield from printing-color pastes often decreases rapidly as the paste ages after being made up, these printing-color pastes are usually prepared by the fabric finishers just before they are to be used.

The printing-color pastes, however compounded, are then applied to textile, paper or other fabric materials for decorative or protective purposes. The printed pieces are dried, aged in a steam ager, treated with an oxidizing agent, rinsed and finally dried. Usually in processing textiles, the printed fabric also is soaped at or near the boil with about a 0.1% soap solution and again rinsed before the final drying operation.

In making up and applying printing-color pastes it has been found that a material suitable for use as a printing assistant is of advantage in obtaining maximum color yield. The exact way in which these materials act to produce an improved color yield in printing is not entirely understood. It is with these printing aids or assistants that the present invention is particularly concerned.

Although printing aids are desirable in the printing-color pastes, the exact point at which they are added may vary. Dye pastes may contain printing aids as one of their components and printing-color pastes made therefrom will obviously contain the printing assistant. Where a printing assistant is not present in the dye paste, it may be added at the time of making up the printing-color paste.

It is preferable, however, that the printing assistant be incorporated in the actual dye paste. Their addition at the proper point in the manu-

facture of the paste is not only easier, but in addition they are thus generally more uniformly dispersed throughout a printing-color paste made therefrom. As a result, the printing assistants usually operate more effectively when the printing-color paste is finally applied to the fabric.

It is only relatively recently that dye powders suitable for use in making up printing-color pastes have been available. Most of the printing aids previously used in dye pastes, being either liquid in form or extremely hygroscopic, can not be used with dye powders, the latter being necessarily limited to the use of dry solids. Nevertheless, it is desirable that printing assistants be incorporated in the powders at the time of manufacture for the same reasons which apply in the case of dye pastes.

Dye pastes containing various liquid printing assistants have been made. Among the liquid materials used are the alkylol amines, for example, triethanol amine; and/or polyhydric alcohols such as glycerine, glycol, diethylene glycol and the like. Various derivatives therefrom also have been tried. If a printing aid is to be incorporated in a dye powder, a solid printing aid is necessary. Examples of such solids which have been used in the past include the hydrochlorides of alkylol amines; silver salt (sodium anthraquinone beta-sulphonate); anthraquinone and certain metal salts such as those of cobalt and iron.

Unfortunately, most of these printing aids previously used are not as satisfactory as may be desired. Many of them will not in all cases produce the intensification of color for which they were intended. Others, such as the polyhydric alcohols, cause deterioration of the printing-color pastes so that marked variations in the strength of prints therefrom are observable even after the printing-color paste has been allowed to stand for only a relatively short time. Many of them are satisfactory with some colors but have an adverse effect on others, even to the extent of visibly altering the shade. None of them are suitable without modification for use both in paste and powder compositions.

There remains, therefore, a demand for suitable printing assistants which will produce a satisfactory color intensification and will not cause deterioration of the dyeing or printing composition on standing. Preferably also, the assistants should be useful both with dye pastes and dye powders and in addition should be readily available or cheaply and easily prepared. It is, therefore, the object of the present invention to pro-

vide a new type of printing assistant which possesses these desirable properties.

In general the objects of the present invention are accomplished by using as a printing assistant a quinonyl-sulphonamide having a terminal polar group. Such compounds may be represented by the general formula

in which Q represents the residue of a quinone such as alpha or beta anthraquinone and beta-naphthoquinone; R₁ and R₂ represent hydrogen or an alkanol, aminoethyl, carbamyl or a condensed carbamyl radical and x may be 1 or 2. Typical of the sulphonamides containing additional polar groups suitable for use according to the present invention are the mono- and di-N-ethanol, beta-anthraquinonylsulphonamides which may be represented by the formulae:

So far as the present invention is concerned the assistants may be added to the printing-color pastes at any point. They may be incorporated into the thickener; into the dye pastes or powders or may be blended directly into the printing-color paste. However, as pointed out above, it is preferable that they be incorporated in the dye paste or powder during manufacture.

The use of this new class of printing assistants possesses a number of important advantages. These compounds are dry solids, which may be readily powdered and blended in dye powders but are also soluble or dispersible in dye paste suspensions. They have, therefore, a general application in both dye pastes and dye powders. They do not cause deterioration of printing-color pastes on standing. They encourage the production of excellent color yields even under hot ageing conditions. Their use is simple since they may be employed as powders, as suspensions in water or alcohol.

In preparing the substituted sulphonamides used as printing assistants according to the present invention, the quinone represented by Q in the generic formula is ordinarily an alpha- or beta-anthraquinone or beta-naphthoquinone. The corresponding derivatives of 1,4-naphthoquinone do not appear to be capable of being isolated, if they form. Also in the case of naphthoquinone, x in the generic formula is ordinarily one since the disulphonamides of naphthoquinone are impractical to form.

Compounds such as those used according to the present invention are readily prepared by condensing a quinone-sulphonic acid with or by reacting a quinone-sulphonyl chloride with a suitable amine. For example, the N-ethanol beta-anthraquinone sulfonamide may be prepared by reacting beta-anthraquinone sulphonyl chloride

with ethanol amine. This compound gives an excellent printing assistant. Similarly, the N-di-ethanol sulphonamides of beta-anthraquinone sulphonic acid may be prepared by reacting the latter with diethanolamine. Other useful products are obtained for example by the condensation of a quinone-sulphonyl chloride and urea, ethylene diamine and the other alkylene diamines, guanidine carbonate, biguanide, melamine and the like.

While the dye and printing paste compositions of the present invention are not limited to the use of any particular dyes or dye forms, they are especially suitable for use with vat-dyes in either paste or powder form. Particularly good results may be obtained using the vat-dye powders of high autodispersibility set forth in Crossley et al., United States Reissue Patent 21,402, reissued March 19, 1940. By combining the color materials of that patent into printing-paste compositions containing the printing assistants of the present invention, the full advantages of both may be gained with a resultant simplicity in use and excellence of shade and sharpness of color.

The invention will be more fully set forth in connection with the following examples which are intended to be illustrative and not by way of limitation. All parts are by weight unless otherwise noted.

In the succeeding examples, test prints were made on two different fabrics. When rayon is referred to, a titanium-dioxide-pigmented, all viscose-rayon flat crepe was used. The cotton fabric referred to is an 80 x 80 bleached, unmercerized, cotton print-cloth. Ageing of the prints was carried out in a steam ager which was constructed in such a manner that controlled temperatures could be used. The temperature range normally used was 100°-105° C. Those ageing referred to as plant or hot ageing were carried out in the temperature range of about 106°-110° C. In the case of the cotton prints ageing periods of 3 minutes, 5 minutes or both were used. On rayon, ageing periods of 5 and 10 minutes or both were used. The shortest period which gives a satisfactory ageing is preferable.

Example 1

A paste was prepared by slurring 2,000 parts of British gum (Stein Hall) in 5,000 parts of water and the mixture was heated with continuous stirring until the temperature reached about 185° F. Heating was continued for about 1½ hours after which 450 parts of powdered sodium carbonate and 450 parts of powdered potassium carbonate were added and the mixture stirred until the carbonates dissolved. Heating was discontinued but stirring continued until the temperature reached approximately 150° F. at which time 700 parts of sodium sulphoxylate formaldehyde were dissolved therein, 600 parts of glycerine were added and the paste bulked to about 10,000 parts with water. Stirring was continued until the paste cooled to room temperature. In the succeeding examples this paste is referred to as thickener A.

Example 2

720 parts of B-2 British gum (Stein Hall) and 720 parts of KAC-4 gum (Stein Hall) were added to 5,600 parts of water and heated over a steam bath for approximately 1½ hours after the temperature reached about 185°-190° F. The source of heat was then removed but stirring is continued until the temperature decreased to 120°

F. at which time 1,200 parts of potassium carbonate which had been previously dissolved in 1,000 parts of water was added to the cooked gum. 1,560 parts of sodium sulphoxylate formaldehyde were dissolved in 1,500 parts of water at a temperature of about 140° F. and added to the common mixture with stirring until the whole was thoroughly mixed. 360 parts of glycerine were added and after thorough stirring the whole was bulked to about 12,000 parts. In the succeeding examples this is referred to as thickener B.

Example 3

2.5 grams of dispersible Golden Orange G powder (C. I.—1096), prepared according to United States Reissue Patent No. 21,402 and containing approximately 0.5 part of real color, were blended with 0.25 part of N-ethanol beta-anthraquinone-sulphonamide. To this was added 97.25 parts of thickener B, and the whole thoroughly mixed to produce a printing-color paste. A duplicate sample of the above was prepared except that no printing assistant was added and the amount of thickener B was 97.5 parts. Both pastes were printed on samples of cotton. The printed pieces were dried in a hot air oven, aged, oxidized, soaped at the boil for five minutes with a 0.1% soap solution, rinsed and finally iron dry. Definitely better prints were obtained from the paste containing the printing assistant.

Example 4

The procedure of Example 3 was repeated except that the Golden Orange G was replaced by Dark Blue BO powder (C. I.—1099). Prints obtained from the pastes containing the printing assistant were definitely stronger and superior to the prints that were made from the paste which contained no assistant.

Example 5

The procedure of Example 3 was repeated except that the condensation product obtained from alpha-anthraquinone-sulphonic acid and monoethanolamine was used in place of the beta-anthraquinone derivative. Prints obtained from the pastes containing the printing assistant were definitely superior to those obtained from the paste which had no printing assistant present.

Example 6

The procedure of Example 5 was repeated except that the Dark Blue powder of Example 4 was used. Prints obtained from the paste in which the printing assistant was present were definitely superior to the color value of the prints obtained from the paste in which no printing assistant was used.

Example 7

A sample of wet presscake of Vat Orange R (C. I.—1217) was dispersed with a sodium salt of disulpho-dinaphthylmethane. After adjusting the mixture with water to contain 12% real color, 10 parts of the mass was mixed with 0.5 part of N-ethanol beta-anthraquinone-sulphonamide. To this was added 89.5 parts of thickener B. A second paste was prepared by mixing together 10 parts of the Vat Orange R and 90 parts of thickener B. This was the control sample. Both pastes were printed on samples of rayon and cotton. The printed pieces were dried in a hot air oven, aged in a steam ager, oxidized, rinsed, soaped at the boil for five minutes in a

0.1% soap solution, rinsed and ironed dry. The prints from the paste containing the printing assistant were much stronger and brighter than from the control.

Example 8

The procedure of Example 7 was repeated exactly except that N-diethanol beta-anthraquinone-sulphonamide was used in place of the printing assistant of the previous example. The prints obtained from the paste in which the substituted beta-anthraquinone sulphonamide was used were definitely superior and brighter than the prints obtained from the paste in which no assistant was present.

Example 9

The procedure of Example 7 was repeated except that N-ethanol alpha-anthraquinone-sulphonamide was used. Again, improved printing was obtained when the printing assistant was used.

Example 10

The procedure of Example 7 was followed using the condensation product of beta-naphthoquinone sulphonic acid and ethanolamine as a printing assistant. As in Example 7, noticeably brighter and clearer prints were obtained when the condensation product was present in the printing paste.

Example 11

The procedure of Example 7 was repeated exactly except that N-(beta-aminoethyl) beta-anthraquinone-sulphonamide was used as the printing assistant. Prints obtained from the paste containing the printing assistant were definitely brighter and stronger than the prints obtained from the paste with water only.

Example 12

The procedure of Example 7 was repeated exactly except that the reaction product of beta-anthraquinone-sulphonic acid and urea was used in place of the N-ethanol beta-anthraquinone-sulphonamide. The color values of the prints which were obtained from the paste in which the printing assistant was present were definitely superior than the color values of the prints obtained from the paste in which no printing assistant was used. This was particularly noticeable when ageings were made under practical mill conditions.

Example 13

The procedure of Example 7 was followed except that the condensation product of beta-anthraquinone-sulphonic acid and melamine was used as the printing assistant. The prints obtained from the paste in which the printing assistant was used were stronger and brighter than the prints obtained from the paste containing thickener only.

Example 14

The procedure of Example 7 was repeated exactly except that printing thickener A was used in place of printing thickener B. Prints made from the paste containing the printing assistant and thickener A were definitely superior to those prints made from the paste containing no printing assistant.

Example 15

5 parts of a Vat Yellow GC dispersed powder (C. I.—1118), prepared according to United States

Reissue Patent No. 21,402 and containing approximately 1 part of real dye were blended with 0.3 part of N-ethanol beta-anthraquinonesulphonamide. To this mixture was added 90 parts of thickener B, and the whole was thoroughly mixed. A second 5 parts of the Vat Yellow GC powder were mixed with 90 parts of thickener B. This was used as a control sample. Both pastes were printed on samples of rayon and cotton and finished in the usual manner. Prints obtained from the paste in which the printing assistant was present were definitely superior in color value to those obtained from the pastes in which no printing assistant was used.

We claim:

1. A color composition comprising a vat dye and a quinone sulphonamide derivative having the general formula

in which Q represents a quinonyl radical selected from the group consisting of the alpha- and beta-anthraquinonyl and beta-naphthaquinonyl radicals, R₁ represents a radical selected from the group consisting of hydrogen and the alkylol, amino alkyl, carbamyl and condensed carbamyl radicals, R₂ represents a radical selected from the group consisting of the alkylol and amino alkyl radicals and x is a small whole number selected from the group consisting of 1 and 2.

2. A dye powder composition comprising a vat dye and a powdered quinone sulphonamide derivative having the general formula

in which Q represents a quinonyl radical selected from the group consisting of the alpha- and beta-anthraquinonyl and beta-naphthaquinonyl radicals, R₁ represents a radical selected from the group consisting of hydrogen and the alkylol, amino alkyl, carbamyl and condensed carbamyl radicals, R₂ represents a radical selected from the group consisting of the alkylol and amino alkyl radicals and x is a small whole number selected from the group consisting of 1 and 2.

3. A dye powder composition comprising a vat dye powder of high autodispersibility and a powdered quinone sulphonamide derivative having the general formula

in which Q represents a quinonyl radical selected from the group consisting of the alpha- and beta-anthraquinonyl and beta-naphthaquinonyl radicals, R₁ represents a radical selected from the group consisting of hydrogen and the alkylol, amino alkyl, carbamyl and condensed carbamyl radicals, R₂ represents a radical selected from the group consisting of the alkylol and amino alkyl radicals and x is a small whole number selected from the group consisting of 1 and 2.

4. A color composition according to claim 1 in which Q represents the beta-naphthoquinonyl group.

5. A color composition according to claim 1 in which Q represents an anthraquinonyl group.

6. A printing paste composition comprising a

5 dye, a thickener and a quinone sulphonamide derivative having the general formula

in which Q represents a quinonyl radical selected from the group consisting of the alpha- and beta-anthraquinonyl and beta-naphthaquinonyl radicals, R₁ represents a radical selected from the group consisting of hydrogen and the alkylol, amino alkyl, carbamyl and condensed carbamyl radicals, R₂ represents a radical selected from the group consisting of the alkylol and amino alkyl radicals and x is a small whole number selected from the group consisting of 1 and 2.

7. A vat dye composition comprising a dye, a thickener and a quinone sulphonamide derivative having the general formula

in which Q represents a quinonyl radical selected from the group consisting of the alpha- and beta-anthraquinonyl and beta-naphthaquinonyl radicals, R₁ represents a radical selected from the group consisting of hydrogen and the alkylol, amino alkyl, carbamyl and condensed carbamyl radicals, R₂ represents a radical selected from the group consisting of the alkylol and amino alkyl radicals and x is a small whole number selected from the group consisting of 1 and 2.

8. A printing paste composition comprising a highly-dispersed vat dye, a thickener and a quinone sulphonamide derivative having the general formula

in which Q represents a quinonyl radical selected from the group consisting of the alpha- and beta-anthraquinonyl and beta-naphthaquinonyl radicals, R₁ represents a radical selected from the group consisting of hydrogen and the alkylol, amino alkyl, carbamyl and condensed carbamyl radicals, R₂ represents a radical selected from the group consisting of the alkylol and amino alkyl radicals and x is a small whole number selected from the group consisting of 1 and 2, obtainable by compounding a colloidized vat dye powder of high autodispersibility and the quinone sulphonamide derivative with the thickener.

9. A method of printing with vat colors which comprises printing a fabric with a printing paste composition comprising a vat dye, a thickener and a quinone sulphonamide derivative having the general formula

65 in which Q represents a quinonyl radical selected from the group consisting of the alpha- and beta-anthraquinonyl and beta-naphthaquinonyl radicals, R₁ represents a radical selected from the group consisting of hydrogen and the alkylol, amino alkyl, carbamyl and condensed carbamyl radicals, R₂ represents a radical selected from the group consisting of the alkylol and amino alkyl radicals and x is a small whole number selected from the group consisting of 1 and 2.

10. An article of manufacture comprising a

fabric printed with a composition comprising a vat dye, and a quinone sulphonamide derivative having the general formula

in which Q represents a quinonyl radical selected from the group consisting of the alpha- and beta-anthraquinonyl and beta-naphthaquinonyl radi- 10

cals, R₁ represents a radical selected from the group consisting of hydrogen and the alkylol, amino alkyl, carbamyl and condensed carbamyl radicals, R₂ represents a radical selected from the group consisting of the alkylol and amino alkyl radicals and x is a small whole number selected from the group consisting of 1 and 2.
